MEDICAL TREATMENT CARRIER

Joel J. Nobel, Philadelphia, Pa., assignor to Graduate
Pain Research Foundation, Philadelphia, Pa., a non-
profit corporation of Pennsylvania

Filed Dec. 10, 1965, Ser. No. 135

Term of patent 14 years

(Cl. D83—1)

Fig. 1

FIGURE 1 is a perspective view taken from the front, the right side, and the top of a medical treatment carrier showing my new design;

FIGURE 2 is an elevational view taken from the rear thereof; and

FIGURE 3 is an elevational view taken from the left side thereof, the bottom being essentially plain and unornamented except for the wheels.

I claim:

The ornamental design for a medical treatment carrier, as shown and described.
